UNITED STATES PATENT OFFICE.

MAX HIRSCH, OF NEW YORK, N. Y.

HEATING APPARATUS.

932,418.

Specification of Letters Patent. Patented Aug. 24, 1909.

Application filed December 30, 1907. Serial No. 408,609.

To all whom it may concern:

Be it known that I, MAX HIRSCH, a subject of the Czar of Russia, residing at Brooklyn, New York city, in the county of Kings 5 and State of New York, have invented certain new and useful Improvements in Heating Apparatus, of which the following is a specification, reference being had therein to the accompanying drawing.

10 My invention relates to improvements in heating apparatus, more particularly, it has reference to an apparatus adapted for use in heating containers of water such as baths, vats or the like.

15 Referring to the accompanying drawings Figure 1 is a side view partly in section showing my heating apparatus. Fig. 2 a plan view of the same and Fig. 3 illustrates a suitable taper which may be used for igniting the apparatus.

20 3 is a flexible tube adapted to supply gas to the burners 4 and 5 with regulating valves 6 and 7 for controlling the supply of gas, and the usual sleeves 8 and 9 for controlling 25 the air supply through the openings 10 and 11.

25 12 is an outer casing hermetically sealed and provided with outlets 13 and 14 and a central passage 15 through which a suitable 30 taper may be introduced for lighting the burners.

35 16 is a suitable taper or torch adapted to be introduced through the opening 15 to ignite the burners 4 and 5 after the gas has been turned on.

17 and 18 are hermetically sealed internal chambers provided with ports such as 19, 20 and 21 which allow the water in the tank, vat or bath, as the case may be, to cir-

culate within same and come in contact with 40 the heat of the burner below.

22 and 23 are extension brackets fastened to the outer casing and bent over at the other end to engage the clips 24 and 25.

27 are brackets fastened to the upper end 45 of the air inlet passage, said brackets and brackets 24 and 25 being provided with openings adapted to receive the bar 26, so that the outer ends of the bar 26 after entering the brackets as aforesaid may rest 50 upon top of the tub, tank or other container in which the heating apparatus is to be used.

Various modifications may be made without departing from the spirit of the invention.

55 Having described the invention, what I claim as new, and desire to secure by Letters Patent is:

In a heating apparatus, the combination 60 with the body comprising the combustion chamber, burners within said combustion chamber, a centrally located air inlet flue, exhaust vents over the burners, said air inlet flue providing access for igniting said burners, multiported water heating chambers 65 over said burners providing for a free circulation of liquid from outside said combustion chamber, said heating chambers located between said burners and said exhaust vents and a carrying frame attached 70 to said apparatus.

In testimony whereof I affix my signature in presence of two witnesses.

MAX HIRSCH.
